[57] CLAIM

The ornamental design for a combined electric shaver and blade cover therefor, as shown and described.

DESCRIPTION

FIG. 1 is a front elevational view of a combined electric shaver and blade cover therefor showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a sectional view with internal mechanisms omitted taken on line VII—VII of FIG. 1;

FIG. 8 is a perspective view thereof;

FIG. 9 is a front elevational view of an electric shaver showing our design with the blade cover removed;

FIG. 10 is a rear elevational view thereof;

FIG. 11 is a top plan view thereof;

FIG. 12 is a bottom plan view thereof;

FIG. 13 is a left side elevational view thereof;

FIG. 14 is a right side elevational view thereof; and

FIG. 15 is a sectional view with internal mechanisms omitted taken on line XV—XV of FIG. 9.
